UNITED STATES PATENT OFFICE

2,130,114

WINDOW VENTILATOR

Charles A. Anderson, New Rochelle, N. Y., assignor to The Gotham Pressed Steel Corporation, New York, N. Y., a corporation of New York

Application August 11, 1937, Serial No. 158,480

7 Claims. (Cl. 98—99)

My invention relates to window ventilators and has particular reference to ventilating deflectors or shields placed in the lower portions of windows.

5 Window ventilators of this type usually have deflectors made of glass plates held in place by end brackets fastened to window frames. When fitting a ventilator to a window, the glass plate must be therefore cut to the exact width 10 between the brackets, this width more or less varying for different windows. Such an operation is highly objectionable, however, rendering the installation difficult and requiring services of an expert glass cutter. In order to avoid this 15 difficulty, two glass plates are sometimes used, telescopically sliding side by side. This arrangement is also objectionable, however, two panes of glass being more expensive and requiring special adjustable braces or rods on top and bottom of the plates, and being less satisfactory 20 from the standpoint of appearance than a single plate.

I have found, however, that it is possible to make horizontally adjustable ventilators, using 25 glass plates of a standardized length and providing adjustment in the end brackets. Windows in ordinary houses vary in width, as a rule, by a few inches only, say between 36 and 40 inches. By making the glass plates 38 inches long, for 30 instance, and the end brackets 3 or 4 inches deep, I can provide a ventilator readily attachable to any ordinary window. An object of my invention is therefore to provide a ventilator of a standardized construction which can be attached to any ordinary window by merely screwing or nailing the end brackets to the window frame.

Another object of my invention is to provide 40 end brackets with detachable holders for the glass plate. By making the holders detachable not only their manufacturing is simplified, but their handling for shipment is facilitated, the knocked down parts occupying much less space than the assembled brackets.

45 Another object of my invention is to provide means for retaining the glass plate in the end holders in a fixed position after the brackets have been fastened to a window frame. For this purpose I provide adjustable blocks in the holders 50 resting against the ends of the glass plate, or adjustable screws or plugs fitted in slots or holes in the holders.

Still another object of my invention is to provide sliding caps for the upper portions of the 55 end glass holders, the caps not only attractively

covering the holders but also serving as clamps to hold the sides of the holders together, the holders being preferably made in the form of U-shaped pieces of sheet metal.

My invention is more fully described in the 5 accompanying specification and drawing in which—

Fig. 1 is a perspective view of my ventilator attached to an ordinary window.

Fig. 2 is a perspective view of an end bracket 10 with a glass plate holder in a detached position.

Fig. 3 is a sectional detail view of the bracket with the glass plate and a spacing block inside.

Fig. 4 is a view taken on the line 4—4 of Fig. 3.

Figs. 5 and 6 are detail views of a modified arrangement for retaining the ends of the glass plate.

Figs. 7 and 8 are similar detail views of another modification.

Fig. 9 is a detail view of still another modification for holding the ends of the glass plate in position.

Figs. 10 and 11 are detail views of still another modification.

My window ventilator consists of end brackets 25 shown in detail in Fig. 2 which may be formed of two pieces 1 and 2 each pivoted together at 3 and telescopically adjustable to different angles of opening as described in my Patent No. 2,016,764. A lug 4 on one piece and a hook 5 on the other 30 prevent the pieces from becoming entirely separated. The outer piece or sector 2 has a flange 6 with rectangular apertures 7, the inner piece 1 having holes 8 for attaching the brackets, which are right and left, to the inner sides of a window 35 frame 9 by screws 10. The apertures 7 are engaged by resilient hooks 11 formed in U-shaped holders 12 for a glass plate 13. The holders are made of sheet metal and the hooks 11 are stamped out to register with the apertures 7. Thus the 40 brackets and the holders can be easily assembled together or taken apart to be packed for shipment. The sides of the holders are spaced apart so as to provide room for the ends of the plate 45 13, the width of the sides of the holders being sufficient to allow for ordinary variations in the width of the windows. I have found that holders 3 or 4 inches wide can be used with a large number of windows, having usually from 36 to 40 inches in width, the glass plate being about 38 50 inches long. In order to prevent longitudinal shifting of the plate after its assembly, I provide spacing blocks 14 in the holders resting against the ends of the plate 13. These blocks are preferably made of wood or similar material which 55

can be easily trimmed by an ordinary penknife or similar tool. The blocks need not fill the holders through the full length and short pieces at the bottom of the holders are sufficient. The 5 top edges 15 and 16 diverge outwardly or flare out so as to make room for a thick upper edge of the glass plate as the latter are usually furnished for this purpose, representing edge portions of sheets made on glass sheet drawing machines.

A cover 17 is slidably fitted over the diverging edges of the holder, the sides of the cover converging so as to engage the diverging edges as shown in Fig. 4. The cover therefore not only 15 encloses the upper portion of the holder but also holds its sides tightly together against the glass plate. The portions 15 are cut away at the outer ends as shown in Fig. 2 at 18 to make room for corresponding tongues or lugs 19 on the flanges 20, this arrangement enabling the covers 17 to hold the pieces 12 more firmly against the flanges 6.

A modified arrangement for retaining the ends of the glass plate is shown in Figs. 5 and 6 showing portions of a U-shaped holder 20 having a horizontal slot 21 for a screw 22 held by a nut 23. The screw has a head 24 resting against the end of the glass plate and a square portion 25 sliding in the slot and preventing the screw from rotation. The screws at both ends of the ventilator, after being tightened against the ends of the glass plate, prevent the latter from moving or shifting longitudinally.

Another modification is shown in Figs. 7 and 8. 35 A holder 26 has an outwardly extending recess 27 with a slot 28 for a square head 29 of a screw 30. A nut 31 is used for tightening the screw. The head 29 is slidably fitted in the recess and therefore cannot turn when the nut is turned.

40 In a modification shown in Fig. 9 the holder 32 has holes 33 for a plug 34 which also rests against the ends of the glass plate.

It is understood that my ventilator can be used with any suitable end brackets, not necessarily 45 of the telescoping type, and single sector-shaped or triangular pieces of sheet metal may be used with flanges 6 for the holders.

In a modification shown in Figs. 10 and 11 the rear side of a U-shaped holder 12' has a flat 50 spring 36 pivoted at 37 and having a head 38 with a handle 39 and a pin-shaped lug 40 fitting in holes 41 arranged concentrically with the pivot 37. The lug 40 extends inside the holder and forms a stop for the end edge of the glass plate

55 13. The plug or lug 40 can be pulled out against the tension of the spring and replaced in any of the holes 41 for retaining the plate 13 in its middle position in the brackets.

I claim as my invention:

60 1. A window ventilator comprising side brackets adapted to be attached to the upright portions of a window frame, U-shaped holders on the brackets of a relatively deep section, a glass plate removably fitted in the holders by its ends, the holders being adapted to retain the glass plate of a standard length with different spacing of the

brackets, and spacing blocks in the holders abutting the ends of the glass plate.

2. A window ventilator comprising side brackets adapted to be attached to the upright portions of a window frame, U-shaped holders on the brackets, a glass plate removably fitted in the holders, the upper portions of the holders diverging outwardly, and U-shaped clips slidably fitted on the diverging portions. 5

3. A window ventilator comprising side brackets adapted to be attached to a window frame, flanges on the outer portions of the brackets, relatively wide U-shaped holders removably attached to the flanges, the bracket flanges having slots, portions of the holders extending into the slots, a glass plate removably fitted in the holders, and U-shaped covers slidably fitted over the upper ends of the holders and over the lugs on the flanges. 10

4. A window ventilator comprising side brackets adapted to be attached to the upright portions of a window frame, flanges on the outer portions of the brackets provided with slots, a glass plate, U-shaped holders removably fitted on the ends of the glass plate, the holders being relatively wide in direction of the glass plate, hooks 25 on the sides of the holders adapted to removably engage the slots on the outer sides of the flanges thereby supporting the holders on the flanges, and means in the holders to abut the ends of the plate. 30

5. A window ventilator comprising side brackets adapted to be attached to the upright portions of a window frame, flanges on the outer portions of the brackets provided with slots, a glass plate, U-shaped holders removably fitted on the ends of the glass plate, the holders being relatively wide in direction of the glass plate, hooks 35 on the sides of the holders adapted to removably engage the slots on the outer sides of the flanges thereby supporting the holders on the flanges, and an adjustable means in the holders to abut the ends of the plate. 40

6. A window ventilator comprising side brackets adapted to be attached to the upright portions of a window frame, flanges on the outer portions of the brackets provided with slots, a glass plate, U-shaped holders removably fitted on the ends of the glass plate, the holders being relatively wide in direction of the glass plate, means on the sides of the holders to detachably engage the outer sides of the bracket flanges for supporting the holders on the brackets, and means to abut the ends of the plate in the holders. 45

7. A window ventilator comprising side brackets adapted to be attached to upright portions of a window frame, flanges on the outer portions of the brackets, U-shaped holders detachably attached to the outer portions of the flanges, a glass plate removably fitted in the holders, the sides of the holders extending in direction of the plate, the joining portions of the holders extending vertically along the outer edges of the glass plate, means to cover the upper ends of the brackets, and means in the holders to abut the ends of the glass plate. 55

CHARLES A. ANDERSON.
